UNITED STATES PATENT OFFICE.

JOSEPH AUGUSTE DECUIR, OF NEW ORLEANS, LOUISIANA.

BICYCLE-PEDAL.

SPECIFICATION forming part of Letters Patent No. 709,306, dated September 16, 1902.

Application filed February 10, 1902. Serial No. 93,432. (No model.)

To all whom it may concern:

Be it known that I, JOSEPH AUGUSTE DECUIR, a citizen of the United States, residing at New Orleans, in the parish of Orleans and 5 State of Louisiana, have made certain new and useful Improvements in Bicycle-Pedals, of which the following is a specification.

The object of my invention is to produce a bicycle-pedal having maximum lightness, 10 strength, durability, and cheapness.

The invention is embodied in the peculiar construction of hubs adapted to rotate upon the spindle of the crank and the form and manner of attachment to the hubs of toothed 15 frames or frame-sections constituting footholds.

The invention further consists in the attachment to the metal sections constituting the frame proper of tubular guards, which 20 are adapted to retain their place upon the toothed portions of the frame by means of their own elasticity, but which may be readily removed as occasion requires.

The details of construction, arrangement, 25 and operation are as hereinafter described, reference being had to accompanying drawings, in which—

Figure 1 is a face view of my improved pedal applied to the spindle of a bicycle-crank. Fig. 2 is a transverse section on the 30 line 2 2 of Fig. 1. Fig. 3 is a perspective view of one of the foot frame-sections or footholds. Fig. 4 is a perspective view of one of the hubs to which the frame-sections or footholds are attached. Fig. 5 is a face view of 35 one of the frame-sections or footholds, the same being represented in the flat. Fig. 6 is a detail section illustrating the antifriction-bearing of one of the hubs with the spindle.

The pedal-frame is made up of three metal 40 sections or subsidiary frames A, the same being riveted together, as shown. Each of these frame-sections A has primarily the form represented in Fig. 5—that is to say, each is 45 a quadrilateral, it being an oblong rectangle, and is formed by cutting it out of sheet metal by means of dies. It may, however, be formed in any other manner. The side bars 1 are provided with teeth, and the end bars 2 are 50 provided with inward projections 2^a, as shown. These projections are bent outward, so as to stand parallel to each other and in a plane

at right angles to the side bars 1, and in practice they constitute the side guards for the pedal, which serve to retain the foot of the 55 rider in place as to lateral movement. The entire body of the end bars 2 is practically turned at right angles to the side bars 1 to adapt them for insertion in slots 3, formed in the angles of the triangular hubs 4, as shown 60 in Fig. 2. In brief, the end bars 2 are twisted so that their middle portions lie practically at a right angle to the side bars 1. The side bars 2 of the toothed frames A are cut out or curved on the outer side at the middle of 65 their length, as shown in Fig. 5, and such curved or cut-out portion fits in the slots 3 of the hubs 4, so that the frame-sections are thus held more firmly in place than would be practical if the outer edges of the said bars 70 were straight. The toothed edges of the frame-sections A are bent outward, the angle being formed a little below the teeth, as shown at 6, Figs. 2 and 3, so that when the bars 1 of adjacent frames are riveted together 75 they lie in contact, while their toothed edges 6 diverge at an obtuse angle, as required to produce a firm foothold. When the three frame-sections are applied to the triangular hubs 4, as shown, and riveted together, they 80 constitute a triangular frame, which is held immovable with relation to the hubs, and therefore revolves with the latter upon the spindle 7 of the bicycle-crank. Each of the two hubs 4 has an antifriction-bearing, as 85 shown in Fig. 6. The frame-sections A are provided with two holes in each of the side bars 1 and a hole at each angle, as shown in Figs. 2, 3, and 5, for receiving the rivets by 90 which the sections are secured rigidly together. It will be seen that this frame has maximum lightness, strength, and rigidity and may be produced at very small cost.

I provide for the several toothed or serrated footholds 6 an elastic guard 8, which 95 is adapted to retain its place by its own elasticity, but may be readily detached when required. Each guard 8 is formed of a section of rubber tubing of due thickness, the same being slotted lengthwise, so that it can be 100 opened and clamped on the serrated portion of foot-rest bar, and when in due position, as shown in Fig. 1, it retains its place by its own elasticity, which causes it to clamp the in-

cluded portions 6 with considerable firmness. It will be seen that this guard 8 may be quickly applied or detached as occasion requires and readily renewed when worn out.

5 Having thus described my invention, what I claim as new, and desire to secure by Letters Patent, is—

1. The improved triangular pedal-frame comprising two hubs and three quadrilateral sections formed of thin plate metal, the plane of the end bars of said sections being at a right angle to that of the side bars and engaged with the hubs, and the side bars being secured together flatwise and their edges forming footholds, as shown and described.

10 2. The improved triangular pedal-frame, formed of hubs provided with peripheral slits or slots and three quadrilateral frame-sections formed of sheet-steel, the end bars of the same being turned at a right angle to the side bars and inserted in the slots of the hubs, and the side bars being riveted together, substantially as shown and described.

15 3. The improved bicycle-pedal frame, comprising triangular hubs having radial slits at their angles and three frame-sections formed of sheet-steel, the end bars of the same being curved or cut out on the outer side, at the middle of their length, and bent at a right

angle to adapt them for insertion in the slits 30 of the hubs, and the side bars of said sections being riveted together and bent outward at their edges to form footholds, substantially as shown and described.

4. The improved pedal comprising triangular hubs having radial slits at their angles, and frame-sections formed of thin sheet metal, in quadrilateral shape, the end bars of the same being provided with projections on their inner sides and twisted or turned, at the middle of their length, at a right angle to the side bars, and their outer edges inserted in the slits of the hubs, the said side bars lying in contact and being serrated and bent outward at their edges to form footholds, substantially as shown and described.

40 5. The combination, with a pedal-frame, having flaring toothed edges constituting footholds, of a guard consisting of an elastic tube slitted lengthwise whereby the tube is adapted to be clamped on such toothed portions, and to clamp the same by its own elasticity and thus retain its position in use, substantially as shown and described.

JOSEPH AUGUSTE DECUIR.
